ATTORNEY.

UNITED STATES PATENT OFFICE.

GEORGE H. BUTZBACH, OF SAN FRANCISCO, CALIFORNIA.

TRICK BASS VIOL.

SPECIFICATION forming part of Letters Patent No. 739,827, dated September 29, 1903.

Application filed March 13, 1903. Serial No. 147,692. (No model.)

To all whom it may concern:

Be it known that I, GEORGE H. BUTZBACH, a citizen of the United States, residing at San Francisco, in the county of San Francisco and State of California, have invented certain new and useful Improvements in Trick Bass Viols, of which the following is a specification.

My invention consists of a trick bass viol 10 for dramatic or amusement purposes, the object of my invention being to provide an instrument of this character which can be used for performing a variety of entertaining tricks or acts, especially in conjunction with dogs 15 or other trained animals.

My invention therefore resides in the novel construction, combination, and arrangement of parts for the above ends hereinafter fully specified, and particularly pointed out in the 20 claim.

In the accompanying drawings, Figure 1 is a front elevation of the instrument with the doors closed. Fig. 2 is a similar view with the doors open. Fig. 3 is a vertical section 25 of the same. Fig. 4 is a bottom end view of the same. Fig. 5 is an enlarged section of a detail.

Referring to the drawings, 1 represents the body of the bass viol, which is indistinguishable, except by a close inspection, from ordinary bass viols. The body is divided into compartments by partitions. One of these partitions 2 extends centrally down the whole length of the viol, and from about two-thirds 35 of the way down there extends laterally a partition 3 on one side to the outside of the viol, forming in the right upper corner thereof a compartment 4, in which may be contained edibles or other articles used in the performance. In the compartment 5 in the upper corner on the left are secured two racks 6, which support bottles, shown at 7, the mouths of which bottles extend downward 40 into the upper portion of a tank 8, open at the top and supported by a door 9, hinged, as shown at 10, on the central partition 2 and dropping down when it is desired to remove the tank to clean the same. In the lower portion of the side wall 11 of said tank is an 45 aperture 12, which registers with an aperture 13 in the outside wall of the viol, and

before filling the tank from the bottles a faucet 14, having a rubber bushing 15, is pushed through both of said apertures, so as to extend into the tank and enable the liquid to 55 be drawn therefrom. The doors 16, which permit access to the compartments 4 5, are held by spring-catches 17, opened by press-buttons 18 from the outside, which press-buttons are flush with the surface of the instrument and being made of the same color as said instrument are invisible except upon close inspection.

The compartment 19 on the right-hand bottom corner is suitable for containing a live 65 domestic animal, such as a dog, and the compartment 20 on the opposite side being smaller in size may contain a smaller animal. Doors 21 open outward and upward at the sides and permit of the dogs entering and 70 leaving said compartments.

The nature of the invention will best be understood by describing the mode of its use. It is intended to be used in connection with a single-act comedy or farce, in which the 75 comedian brings the double bass viol upon the stage with the dogs in their compartments and with the various refreshments or other articles also in place. The instrument is drawn onto the stage on a small truck, 80 and when in such position the doors 21 of the dog-compartments are opened and the dogs are allowed to escape therefrom, whereupon they proceed to perform the tricks, musical or otherwise, to which they have been trained. 85 In the course of the performance the comedian will insert the faucet through the two apertures, will open the door leading to the liquid-compartment, will open the bottles of beer or others placed therein with their necks 90 downward, and will draw the beer from the tank through the faucet. He will also reach into the other compartment and will draw solid refreshments or other articles therefrom that may be necessary for the performance of 95 the comedy.

I claim—

A bass viol having in the lower portions of its body compartments and doors for said compartments opening outward from the 100 sides of the instrument, having also compartments in the upper portions of the bass viol,

one of said compartments being provided with a rack for an inverted bottle, a tank contained in the instrument open at the top and arranged to receive the liquid discharged from 5 a bottle in the rack, a door swinging downward and, when closed, supporting said tank in position, the tank and the wall of the instrument having registering apertures, and a faucet passed through both of said apertures

for drawing the liquid from said tank, substantially as described.

In witness whereof I have hereunto set my hand in the presence of two subscribing witnesses.

G. H. BUTZBACH.
